METHOD FOR ELECTROLYTIC DETERMINA- TION OF LEAD AND COPPER

Robert W. Notvest, Affton, Mo., assignor to Amer-
ican Brake Shoe Company, New York, N. Y., a
a corporation of Delaware

Application February 10, 1948, Serial No. 7,366

1 Claim. (Cl. 204—1)

1

This application is a continuation-in-part of applicant's copending application, Serial No. 549,995, filed August 18, 1944 and entitled "Method of Electroanalysis," now abandoned.

This invention relates to a method for the electrolytic quantitative analysis or determination of copper and lead in copper-bearing and lead-bearing metals or alloys.

In the quantitative analytical determination or analysis of copper and lead in copper-bearing and lead-bearing metals or alloys, or other specimens, in acid solutions, these metals are electrolytically deposited as metallic copper and as lead oxide (PbO_2) upon a platinum wire gauge cathode and anode, respectively, of known weight. In the case of copper, the copper content of the metal or other specimen under analysis is then determined by calculating the difference in the weight of the platinum cathode before and after the copper is deposited thereon. Similarly, in the case of lead, the lead content of a metal or other specimen under analysis is calculated by determining the weight of the lead oxide (PbO_2) deposited upon the platinum anode and then calculating the weight of the lead in the deposited lead oxide in accordance with the percentage composition of the lead oxide.

However, a number of problems have been experienced heretofore in the electroanalysis of copper and lead in acid solutions and these problems have not heretofore, insofar as I am aware, been successfully solved.

Thus among the problems which have been experienced heretofore in the quantitative electrolytic determination of copper and lead in copper-bearing and lead-bearing metals or alloys in acid solutions are the fact that such metals or other specimens usually contain small percentages of arsenic, iron, sulphur and phosphorus, and the presence of small percentages of these elements, and resulting deposits thereof upon the platinum electrodes materially complicates the problem of making accurate analytical determinations of the copper and lead contents of such metals or other specimens. Hence it has been customary practice heretofore in the art to remove these elements, as well as other elements including antimony, tin, molybdenum, gold, platinum, silver, mercury, bismuth, selenium and tellurium, before attempting to make accurate quantitative determinations of copper and lead in acid solutions. (Applied Inorganic Analysis by Hillebrand and Lundell, John Wiley and Sons, 1929, pages 197, 198.)

However, prior procedures which have required the removal of arsenic, iron, sulphur, phosphorus, antimony, tin, molybdenum, gold, platinum, silver, mercury, bismuth, selenium and tellurium from copper-bearing and lead-bearing metals, ores, or other specimens have rendered such prior

2

methods slow and relatively costly to operate in commercial laboratory practice.

Moreover, another difficulty which has been experienced in the electrolytic quantitative determination of copper and lead has been the fact that the oxygen and NO_2 which accumulate upon the anode during the electrolysis tend to adhere firmly to the anode where they retard deposition, cause spongy deposits of PbO_2 , and otherwise generally cause inaccurate quantitative results, unless eliminated.

A further difficulty which has been experienced in the use of prior methods and apparatus for the electrolytic determination of copper and lead has been the fact that in the use of prior art methods and apparatus it was impossible to make an exact quantitative determination of copper in a copper-bearing metal or ore if the specimen contained more than 0.1 per cent of iron. This was due to the fact that the iron content of the specimen would react with the HNO_3 used in the electrolysis to form ferric nitrate which is an excellent solvent for copper, and tends to dissolve the metallic copper deposited upon the cathode and thus cause inaccurate quantitative determinations of copper. Thus the solvent action of the ferric nitrate has made it especially difficult to release all of the Cu ions from the electrolyte and to deposit the same upon the cathode. This solvent action of HNO_3 upon copper is particularly noticeable in the presence of NO_2 in the electrolyte.

However, in the practice of the present invention it is possible to make accurate quantitative determinations of copper in copper-bearing metals and ores which contain as much as 1.5 or even 2.0 per cent iron.

Another difficulty which has been experienced in the use of prior methods and apparatus for the quantitative electrolytic determination of copper and lead is the fact that oxidizing gases, such as NO_2 and O_2 , formed in the electrolyte during the electrolysis, tend to migrate to and to adhere firmly to the anode whereas, on the other hand, reducing gases such as H_2 and NH_3 tend, of course, to migrate to but do not tend to adhere firmly to the cathode. However, the adherence of such oxidizing gases as NO_2 and O_2 upon the anode tends to build up the internal resistance of the electrolyte, thereby causing excessive overvoltage with resulting formation of spongy and irregular and loosely adhering deposits of metallic copper and PbO_2 upon the cathode and anode, respectively.

The foregoing and other problems which are involved in the quantitative electrolytic determination of copper and lead have been recognized heretofore in the art and attempts have been made in various ways to overcome these difficulties. Thus, for example, mechanical electrolyte

stirring devices, rotating electrodes, and other mechanical devices have been employed and air stirring of the anode by the introduction of air into the electrolyte have all been employed. However, none of these prior mechanical devices or methods has, insofar as I am aware, been entirely successful, for a number of reasons. Thus one of the serious difficulties involved in the use of mechanical electrolyte stirring devices is the fact that such mechanical electrolyte stirring devices tend to dislodge the deposits of copper and PbO_2 from the cathode and anode, respectively, whereas agitation or scouring of the anode with air, while tending to dislodge the firmly adhering oxidizing gases such as NO_2 and O_2 from the anode, has no chemical effect in preserving the pH of the electrolyte within desired limits or in preventing imbalance and resulting overvoltage of the electrolyte with consequent formation of spongy and irregular-shaped and loosely adhering deposits of copper and PbO_2 upon the cathode and anode, respectively. Moreover, the use of rotating electrodes, not only tends to dislodge the deposit accumulated thereon but renders it difficult to maintain the characteristics of the current and of the electrolyte employed constant during the electrolysis.

Accordingly, an object of the present invention is to provide a new and improved method for the quantitative electrolytic determination of copper and lead in copper-bearing and lead-bearing metals and ores and which, in use, overcome the foregoing and other difficulties experienced in the use of prior methods and apparatus for the quantitative electrolytic determination of copper and lead.

An additional object of the present invention is to provide a new and improved method for the quantitative electrolytic determination of copper and lead and in the use of which more exact and more rapid quantitative electrolytic determinations of these metals can be made than has been possible heretofore in the use of prior methods and apparatus.

A further object of the invention is to provide a new and improved method for the quantitative electrolytic determination of copper and lead and in the use of which deposition-retarding and oxidizing gases, such as NO_2 and O_2 , which tend to gather upon and to adhere to the anode, and to cause spongy and loosely held deposits thereon, are continuously and thoroughly removed from the anode during the electrolysis without dislodging therefrom the PbO_2 deposited thereon.

A further object of the invention is to provide a new and improved method for the electrolytic determination of copper and which in use make it possible to obtain accurate quantitative determinations of copper in specimens containing as much as 2.0 per cent of iron.

Still another object of the invention is to provide a new and improved method for the quantitative electrolytic determination of copper and in the use of which the internal resistance of the electrolyte due to oxidation of the HNO_3 to NH_3 is minimized and the pH of the electrolyte is maintained within the range of from 5.0 to 5.5, and the current density is, therefore, kept substantially constant, thereby assuring good firm deposits of metallic copper upon the cathode and good firm deposits of PbO_2 upon the anode.

Another object of the present invention is to provide a new and improved method for effect-

ing the relatively rapid and yet highly accurate quantitative determination of copper and lead in copper-bearing and lead-bearing metals, ores, or like specimens, in acid solution, and without the necessity for the prior separation from such specimens of such quantities of arsenic, iron, sulphur, phosphorus, molybdenum, selenium and tellurium, as may be present therein.

In the drawing:

Fig. 1 is a side elevational view, partly in section, illustrating a preferred form of electrolysis apparatus which may be employed in the practice of the present invention;

Fig. 2 is a vertical sectional view illustrating the construction of the anode and related parts of the electrolysis apparatus shown in Fig. 1;

Fig. 3 is a bottom plan view, on line 3—3 in Fig. 2, illustrating the construction of the anode apparatus shown in Fig. 2;

Fig. 4 is a top plan view, on line 4—4 in Fig. 2, of the anode apparatus shown in Fig. 2; and

Fig. 5 is a partial sectional plan view on line 5—5 in Fig. 1.

A preferred form of the electrolytic apparatus which may be employed in the practice of the present invention is illustrated in the drawing, wherein it is generally indicated at 10, and comprises an anode unit, which is generally indicated at 11, and a cathode unit which is generally indicated at 12, both of which are shown as being arranged in an electrolytic beaker 13. The anode unit 11 includes a tubular metal combination current-conducting and gas-conducting member 14 to which a lead-in conductor 15 may be attached for connection to a suitable current source. The anode unit 11 also includes a preferably sandblasted and substantially cylindrical platinum wire gauze electrode 16 of suitable mesh. The combination current-conducting and gas-conducting tubular member 14 extends through a central opening 18 which is provided in a spider member 17 which is attached in any suitable manner, as by a friction fit, upon the open upper end portion of the platinum wire gauze anode electrode 16 (Figs. 2 and 4). The lower end portion 19 of the combination current-conducting and gas-conducting tubular member 14 extends downwardly below the open lower end of the platinum wire gauze anode electrode 16 where the said lower end portion 19 of the said tubular member 14 is secured, in any suitable manner, as by welding, in a central opening 20 which is formed in a substantially circular closure member or cap 21 having an upper flanged portion 22 which is attached in any suitable manner, as by welding, to the outer surface of the lower end portion of the substantially cylindrical platinum wire gauze anode electrode 16 (Figs. 2 and 3). As shown in Figs. 2 and 3, the lower end portion 19 of the tubular member 14 has an open lower end 24 which opens onto and below the lower surface 25 of the closure member or cap 21 and which is curved convexly downwardly, as best shown in Fig. 2.

The anode unit 11 is completed by a flexible rubber tubular member 28 which is attached to the open upper end portion of the combination current-conducting and gas-conducting tubular member 14 so that the said tubular member 14—28 may be connected to a suitable source of carbon dioxide under pressure of from 1 to 15 pounds per square inch.

The usual procedure followed in the practice

of the present invention is illustrated in the following example:

EXAMPLE 1

In the practice of the present invention, a 1 gram sample of a copper-containing and lead-containing metal may be dissolved in from 7 to 10 c. c. of concentrated HNO_3 or, if the resulting reaction between the concentrated HNO_3 and the metal is too vigorous, the acid may be diluted with an equal volume of distilled water. After the initial vigorous reaction between the acid and the metal subsides approximately 50 c. c. are added and the solution is kept at a temperature near boiling, on a hot plate, for a period of at least 30 minutes. During this phase of the operation the tin and antimony contents of the specimen, if any, will be precipitated as SnO_2 and Sb_2O_3 and these oxides, as precipitated, will carry down with them, out of the solution, a part of the iron content, if any of the specimen, together with most of the phosphorus content thereof. Since SnO_2 and Sb_2O_3 are soluble at temperatures below 65° C., but are insoluble at temperatures in excess of 65° C., the thus precipitated SnO_2 and Sb_2O_3 are filtered from the solution while the latter is kept hot. The filtrate solution is then ready to be electroanalyzed for its copper and lead contents.

The procedure thus described is the general procedure followed in preparing most specimens of copper-bearing and lead-bearing metals and ores for electroanalysis according to the method of the present invention and is varied only in those instances in which the sample or specimen is an aluminum bronze or a manganese bronze in either of which cases a one gram sample or specimen is dissolved in a hydrofluoric acid-resistant beaker with 7 c. c. of concentrated HNO_3 and from 3 c. c. to 5 c. c. of hydrofluoric acid. This procedure keeps all of the tin and antimony in suspension so that the electroanalysis or quantitative determination of the copper and lead contents of the specimen may be accomplished without the prior removal of the tin and antimony contents of the aluminum bronze or manganese bronze specimen.

The electrolyte thus prepared is then transferred to the beaker 13 (Fig. 1) and the anode unit 11 and the cathode unit 12 are immersed therein whereupon the control valve (not shown) for the CO_2 supply to the combination current-conducting and gas-conducting member 14-28 is adjusted to produce a steady flow of CO_2 at a selected pressure of from 1 to 5 pounds per square inch through the tubular member 14-28, whereupon the current from the lead-in conductors 15 and 27 to the anode and cathode units 11 and 12, respectively, is turned on. The electrolysis thereupon proceeds in the electrolysis beaker 13, the copper content of the electrolyte being deposited as metallic copper upon the substantially cylindrical platinum gauze cathode 29 and the lead content of the electrolyte being deposited as PbO_2 upon the substantially cylindrical platinum gauze anode 16.

It has been found, in the practice of the present invention, that when the acid content of the electrolyte is relatively high all of the lead content of the electrolyte is deposited as PbO_2 upon the anode 16 within a period of from 10 to 12 minutes from the time the electrolysis is begun depending, in part, upon the current density, voltage, and other variables.

In order to produce a sharper separation of the

copper content of the electrolyte, and a better grained and more firmly adhering deposit of metallic copper upon the cathode 29, 2 c. c. of concentrated H_2SO_4 are at this stage of the electrolysis added to the electrolyte in the beaker 13 and the electrolysis continued until a spot test of one drop of the electrolyte with H_2S water shows that all of the lead content and all of the copper content of the electrolyte have been deposited upon the anode 16 and upon the cathode 29, respectively.

The current to the lead-in conductors 15 and 27 and the flow of CO_2 through the tubular member 14-28 may then be shut off and the anode 15 and cathode units 11 and 12, respectively, removed from the beaker 13. The anode unit 11 may then be dried in an electric oven for a period of about 30 minutes, at a temperature of about 200° C., and then weighed with the thus dried deposit of PbO_2 thereon. The cathode unit 12 and the deposit of metallic copper thereon may then be dipped in boiling water and alcohol and then dried for a period of 2 minutes at a temperature of 110° C. Upon subtracting from these weights the net known weights of the anode and cathode units 11 and 12, respectively, the weight of the metallic copper deposited upon the cathode 29 and the weight of PbO_2 deposited upon the anode 16 may be determined and the copper and lead contents of the specimen or sample thus analyzed readily calculated.

It has been found in the practice of the present invention that as the CO_2 flows downwardly through the combination tubular current-conducting and gas-conducting anode member 14 it emerges in the form of a steady stream of CO_2 bubbles from the open lower end 24 of the tubular member 14 whence the CO_2 bubbles pass upwardly over the convexly downwardly curved bottom surface 25 of the closure member or cap 21 which is attached to the lower end portion of the substantially cylindrical platinum gauze anode member 16.

Moreover, it has also been found in the practice of the present invention that as the CO_2 bubbles emerge from the open lower end portion 24 of the tubular member 14 and travel upwardly in the electrolyte over the convexly downwardly curved lower surface 25 of the member 21 the said convexly downwardly curved lower surface 25 of the member 21 imparts a whirling motion to the CO_2 bubbles and as the stream of whirling CO_2 bubbles pass upwardly in the electrolyte over the external surface of the substantially cylindrical platinum gauze anode 16 the said CO_2 bubbles create a turbulence and exert a scouring action upon the said platinum gauze anode 16 and upon the deposit of PbO_2 thereon and which results are not obtained when the bottom of the closure member 21 is formed as a square or other substantially flat surface. In this manner substantially all of the deposition-retarding and oxidizing gases, including O_2 and NO_2 , which accumulate upon the platinum gauze anode 16 and upon the PbO_2 deposit thereon (and which deposition-retarding and oxidizing gases would otherwise cause spongy and loosely held deposits of PbO_2 as well as building up the internal resistance of the electrolytic cell), are removed from the platinum gauze anode 16 and the PbO_2 deposit thereon in status nascendi. In this manner good uniform and firmly held deposits of PbO_2 on the anode 16 are assured, the internal resistance of the electrolytic cell is minimized

75 and overvoltage in the electrolytic cell is elimi-

nated, oxidation and resulting staining of the copper deposited on the cathode 29 are prevented and good firm deposits of salmon-colored copper on the cathode 29 are obtained, the tendency of the ferric nitrate content in the electrolyte to increase with resultant corresponding increase in the solvent action of the ferric nitrate upon the copper deposited on the cathode 29 is counteracted and reduced, and more accurate quantitative electrolytic determinations of both lead and copper are assured.

It has also been found in the practice of the present invention that the steadily flowing stream of CO_2 bubbles thus passed into the electrolyte not only exerts a mechanical scouring or cleaning function upon the platinum anode 16 and upon the PbO_2 deposit thereon, so as to remove in status nascendi the deposition-retarding and oxidizing gases, such as O_2 and NO_2 , which would otherwise adhere and cling to the anode 16 and the PbO_2 deposit thereon, but the steady flow of CO_2 thus passed into the electrolyte during the electrolysis performs a second but not fully understood function which is believed to reside in the formation of carbonic acid (H_2CO_3) in the electrolyte and which tends to neutralize the NH_3 which is formed in the electrolyte, particularly in the latter stages of the electrolysis. Hence it is believed that the CO_2 thus functions to maintain a definite acidity in the electrolyte throughout the electrolysis and thus keeps the temperature of the electrolyte down, preserves a more uniform current flow through the electrolyte, and thus accelerates and promotes the deposition of the last traces of copper and lead in the electrolyte upon the cathode and anode, respectively, with correspondingly more accurate quantitative electrolytic determinations of these metals than has been possible heretofore in the use of prior methods and apparatus. That such a second function is performed by the CO_2 , in addition to its function of mechanically scouring the platinum anode 16 and the PbO_2 deposit thereon, is shown by the fact that if a stream of air is passed through the tubular anode member 14-28, in place of a stream of CO_2 , but under otherwise identical conditions, and with all other variables controlled, the results in terms of quantitative electrolytic determinations of copper and lead are significantly and consistently less accurate than when a stream of CO_2 is employed, as in the practice of the present invention. That this is so may be seen by reference to the following comparative examples.

Thus a typical analysis of a sample of brass, of known composition, to determine its lead and copper contents, following the practice of the present invention, is illustrated in the following example:

EXAMPLE 2

The cathode 29 was formed of a sandblasted 45 mesh platinum gauze cylinder which was 35 mm. in diameter and 50 mm. in height. The anode 16 was formed of a sandblasted 45 mesh platinum cylinder which was 15 mm. in diameter and 50 mm. in height. After an initial polarizing period of one minute the current in the electrolytic cell was adjusted by means of a rheostat to two amperes at an average potential of 2.2 volts and the current was held constant at this density and voltage throughout the analysis. A certified National Bureau of Standards sample of brass weighing 1.000 gram, plus or minus 0.1 milligram, and having the certified

composition hereinafter set forth, was then dissolved in 10 cc. of concentrated HNO_3 , baked to dryness, redissolved in 70 cc. of concentrated HNO_3 , digested with 30 cc. of boiling water for 20 minutes, and then filtered through a No. 42 Whatman filter paper at a temperature slightly in excess of 70° C. The filtrate was then cooled to room temperature, diluted to approximately 100-110 cc., and placed in the beaker 13. The electric current was then adjusted and the CO_2 gas was then passed through the tube 14 as set forth above. After twenty minutes of elapsed electrolysis time 40 cc. of 1-1 H_2SO_4 were added to the electrolyte in the beaker 13. After disappearance of the blue color in the electrolyte, a small quantity of hydrazine sulphate was then added to the electrolyte to accelerate the deposition of the last traces of Cu ions. Completion of the electrolysis was ascertained by repeated additions of a drop of the electrolyte to a small specimen or pool of H_2S saturated water on a porcelain spot-plate until no yellow discoloration took place. Upon completion of the electrolysis the parts of the anode unit 11 and the parts of the cathode unit 12 were dipped in a solution of boiling water and methyl alcohol and then dried in an electric oven before weighing. Thus the parts of the cathode unit 12 were dried for a period of from 2 to 3 minutes at a temperature of 110° C. and the parts of the anode unit 11 and the deposit of PbO_2 thereon were dried for a period of 45 minutes at a temperature of 200° C., whereupon the thus dried parts of the cathode unit 12 and the thus dried parts of the anode unit 11 and the deposit of PbO_2 thereon were then weighed and the weight of the Cu and PbO_2 deposit on the anode unit 11 determined.

Four samples of the same certified specimen 40 of brass were analyzed in the manner set forth above and the accuracy of the analyses made may be seen by comparing the results obtained with the certified known composition of these brass specimens as furnished by the United States Bureau of Standards, as follows:

Certified composition of sample

Percentage by weight	
50 Copper	83.77
Lead	4.78
Zinc	5.46
Tin	4.69
Nickel	0.45
Tin	0.38
Antimony	0.23
Silicon	0.075
Sulphur	0.071
Phosphorus	0.037
60 Aluminum	0.016

Copper and lead contents of brass sample as obtained by the method of Example 2

Specimen Number	Element	Electrolysis Time in Minutes	Percentage by Weight
70 1	Copper Lead	43	83.78
	do	43	83.74
2	do	43	4.75
3	do	48	83.77
4	do	48	4.77
			83.76
			4.78

EXAMPLE 3

In order to illustrate the greatly reduced deposition time and resulting increased speed of electrolysis and the markedly higher degree of accuracy in the results obtained a specimen of the same United States Bureau of Standards sample of brass referred to above, and having the certified composition set forth above, was analyzed exactly in accordance with the method and the conditions set forth in the foregoing Example 2 except that the CO_2 flow through the anode tube 10 was shut off and the electrolysis made without passing CO_2 into, or otherwise agitating, the electrolyte. The results obtained were as follows:

Specimen Number	Element	Electrolysis Time	Percentage by Weight
1.....	Copper Lead	Hours 5	{ 79.83 4.68

EXAMPLE 4

In order to illustrate the greatly reduced deposition time and the much greater accuracy in the quantitative determinations of lead and copper obtained when directing a steady stream of CO_2 through the tubular anode member 14-28, as compared with the results obtained when air, rather than CO_2 was directed into the electrolyte through the tubular anode member 14-28, analyses of the same certified Bureau of Standards brass sample were run exactly in accordance with the method and conditions set forth in the foregoing Example 2 except that air, rather than CO_2 was allowed to flow through the tubular anode member 14-28 under exactly the same pressure and conditions as were employed in the use of the CO_2 . The results were as follows:

Specimen Number	Element	Electrolysis Time	Percentage by Weight
1.....	Copper Lead	1 hour, 55 min	{ 83.59 4.74
2.....	do	2 hours, 10 min	{ 83.63 4.67
3.....	do	2 hours, 5 min	{ 83.55 4.80
4.....	do	2 hours, 10 min	{ 83.69 4.76

EXAMPLE 5

Similarly, a certified Bureau of Standards sample of phosphor bronze was analyzed exactly in accordance with the method and under the conditions set forth in the foregoing Example 2, with the following results:

Certified composition of sample

	Percentage by weight
Copper	78.50
Lead	8.92
Tin	9.79
Zinc	0.61
Phosphorus	0.59
Iron	0.52
Antimony	0.50
Nickel	0.32
Sulphur	0.11
Arsenic	0.026
Aluminum	0.001

Copper and lead contents of sample of phosphor bronze as determined by the method of Example 2

Specimen Number	Element	Electrolysis Time in Minutes	Percentage by Weight
1.....	{Copper Lead	41	{ 78.45 8.95
2.....	{Copper Lead	41	{ 78.44 8.94
3.....	{Copper Lead	45	{ 78.44 8.89
4.....	{Copper Lead	45	{ 78.46 8.93

EXAMPLE 6

In order further to illustrate the greatly reduced deposition time and the greater accuracy in the quantitative determination of lead and copper which are obtained when passing a stream of CO_2 through the tubular anode member 14-28 into the electrolyte, specimens of the same Bureau of Standards sample of phosphor bronze, having the certified composition set forth above, were analyzed exactly in accordance with the method, and under the conditions set forth in Example 2, above, except that the flow of CO_2 through the tubular anode member 14-28 was shut off and the electrolysis was made without agitating the electrolyte in any way. The results were as follows:

Specimen Number	Element	Electrolysis Time	Percentage By Weight
1.....	{Copper Lead	Hours 5	{ 74.94 8.29
2.....	{Copper Lead	5	{ 76.50 8.31

EXAMPLE 7

In order further to illustrate the greatly reduced deposition time and the much greater accuracy obtained when directing a stream of CO_2 through the tubular anode member 14-28 into the electrolyte, as compared with the results obtained when employing air in place of CO_2 , analyses of the same certified Bureau of Standards sample of phosphor bronze were made exactly in accordance with the method, and under the conditions, set forth in Example 2, except that a stream of air, rather than CO_2 , was directed through the tubular anode member 14-28, under exactly the same conditions as were employed in the use of CO_2 . The results were as follows:

Specimen Number	Element	Electrolysis Time	Percentage By Weight
1.....	{Copper Lead	1 hour, 57 min	{ 78.14 8.89
2.....	{Copper Lead	1 hour, 57 min	{ 78.23 8.90
3.....	{Copper Lead	1 hour, 30 min	{ 78.30 8.88
4.....	{Copper Lead	1 hour, 30 min	{ 78.33 8.86

In place of the nitric acid-sulphuric acid electrolyte which was employed in the analyses of the specimens of brass in Examples 1 to 4, inclusive, and in the analyses of the specimens of phosphor bronze, as in Examples 5, 6 and 7, an electrolyte consisting of a mixture of nitric acid and hydrofluoric acids may be employed in the practice of the present invention as when analyzing a specimen of aluminum bronze or manganese

bronze to determine the copper and lead contents thereof. Thus a specimen of manganese bronze was analyzed in the apparatus illustrated in the drawing, according to the procedure illustrated in the following example:

EXAMPLE 8

A specimen of manganese bronze weighing 1.000 gram was placed in a 200 c. c. hydrofluoric acid resistant beaker. The following materials were then added to the beaker in the order named: 15 c. c. H_2O ; 1 c. c. 48 per cent water solution of hydrofluoric acid; and 7 c. c. concentrated HNO_3 . The beaker was then covered with a platinum lid, and the electrolyte allowed to stand, without heating, until the sample was entirely dissolved, whereupon the solution was boiled briefly to drive off excess NO_2 . The solution was then cooled to room temperature, the lid and beaker rinsed with water, the solution diluted with H_2O to 200 c. c., and the electrolyte then placed in the beaker 13 of the electrolysis apparatus shown in the drawing. The current density was then adjusted to from 1.075 to 2 amperes, and the CO_2 stream through the tubular anode member 14-28 turned on. The electrolysis was thereupon allowed to proceed and the entire lead content of the specimen was deposited as PbO_2 upon the anode, which was accomplished in 20 minutes. 4 c. c. 1-1 H_2SO_4 were then added to the electrolyte and the analyses then completed in the manner set forth in Example 1.

The hydrofluoric acid content of the electrolyte employed in the foregoing Example 8 serves to keep the antimony and tin content of the specimen of manganese bronze in solution so that it will not contaminate either the copper or the lead dioxide (PbO_2) deposit during the analyses to determine the copper and lead contents of the specimen of manganese bronze.

The results obtained in the determination of the lead and copper contents of specimens of manganese bronze according to the method of the present invention are equally as accurate as the results obtained in determining the lead and copper contents of samples of brass and phosphor bronze, and similar copper-bearing and lead-bearing metals, as in Examples 1 to 7, inclusive, above.

Moreover, in the practice of the present invention it has been found possible to obtain accurate and rapid electroanalyses of copper in the presence of substantially greater percentages of bismuth and iron than has been possible heretofore, notwithstanding the strong solvent action of iron, in the form of ferric nitrate, upon copper deposited upon the cathode during the electroanalyses. Thus accurate and rapid quantitative determinations of copper have been obtained from brass samples, using HNO_3 - H_2SO_4 as the electrolyte, in the presence of as much as 0.5 per cent iron in the sample, and in the analysis of specimens of bronze, using HNO_3 -HF as the electrolyte, accurate quantitative determinations of copper have been obtained in the presence of as much as 3.0 per cent iron in the sample.

It will thus be seen from the foregoing description, considered in conjunction with the accompanying drawing, that the present invention provides a new and improved method for the rapid and accurate quantitative electrolytic determination of lead and copper in lead-bearing and copper-bearing metals, ores, and the like, and that the invention thus has the desirable advantages and characteristics, and accomplishes its intended objects, including those hereinbefore pointed out and others which are inherent in the invention.

I claim:

15 In a method for the quantitative electrolytic determination of lead and copper in lead-copper materials, the improvement which resides in dissolving a sample of the material in nitric acid to form an electrolytic solution, electrolyzing said solution in the presence of a cathode and a cylindrical gauze anode to cause the lead content of the solution to be deposited as PbO_2 on said anode and the copper content of the solution to be deposited on said cathode, passing a continuous stream of CO_2 gas into the solution immediately below said anode during the electrolysis so that the said CO_2 gas will travel upwardly through the solution and create a turbulence about the anode and thus exert a scouring action upon the anode and upon the PbO_2 deposited thereon to remove oxidizing gases such as O_2 and NO_2 which tend to accumulate upon and adhere thereto, adding sulphuric acid to the solution after substantially all of the lead content of the solution has been deposited as PbO_2 on the anode to improve the grain structure of the copper deposited upon the cathode and to cause the copper to adhere more firmly thereto and continuing the electrolysis until substantially all the copper has been deposited on the cathode.
